Specification of Letters Patent. Patented Dec. 14, 1915.

Application filed September 11, 1912. Serial No. 719,735.

To all whom it may concern:

Be it known that we, EDWIN L. UPSON, a citizen of the United States, residing at Brooklyn, in the county of Kings and State 5 of New York, and HENRY W. PLEISTER, a citizen of the United States, residing at Westfield, in the county of Union and State of New Jersey, have invented certain new and useful Improvements in Percussion-

10 Hammers, of which the following is a specification.

Our present invention relates to an improvement in percussion hammers which may be used for tamping, or cutting holes in 15 hard substances, or for riveting, or any other use which requires a rapid succession of blows to perform the necessary operation.

One of the objects of our improvement is in the construction of the hammer operating 20 device whereby the operator thereof is enabled to perform the required amount of work with the minimum amount of muscular effort.

Heretofore in tools of this type, a great 25 amount of effort was required on the part of the operator to manually operate the device owing to the great amount of spring tension that was placed upon the hammer. This spring tension is for the purpose of storing 30 energy and to give the necessary impact through the hammer to the tool, and in our present construction we have so arranged the lifting elements of the hammer, that the force necessary to overcome the energy storing 35 means is greatly reduced.

A further object is the provision of a simple means whereby the operator may increase or decrease the force of the blow given to the operating tool being used.

40 These objects and other advantageous features will now be described in detail.

Figure 1 shows the side elevation of our device, with a portion broken away to show the interior thereof; Fig. 2 is a front elevation of the same; Fig. 3 is a diagrammatic view of the device; Fig. 4 is another diagrammatic view showing another position of the operating elements; Fig. 5 is a front elevation of the hammer reciprocating member; Fig. 6 is a sectional view of the same taken on the line 6-6, Fig. 5; Fig. 7 is an end view of the hammer, shown in Fig. 8 in side elevation; Fig. 9 is a fragmentary view taken on the line 9-9, Fig. 4, looking in the 55 direction of the arrow; Fig. 10 is a frag-

mentary view showing a modification of the device; Fig. 11 is another view of the said modification showing certain positions of the relative parts; Fig. 12 is a fragmentary section taken on line 12-12 of Fig. 10; Fig. 13 is a sectional view of the hammer and operating member on line 13-13 in Fig. 11, and, Fig. 14 is a sectional view taken on the line 14-14 of Fig. 11.

In Figs. 1 and 2 our device is shown as being comprised of a housing portion 1, and has arranged at the upper end of the said housing a hub or boss 2 which has a threaded socket 3 therein which receives a correspondingly threaded stud member 4, which 60 stud member carries on its opposite end a rotatable arm or breast plate member 5. Said member 5 is rotatably mounted to permit swinging of the tool about its tool axis during operation, and in one method of 70 mounting it is shown as having a depressed seat 6 therein into which the stud 4 projects, and upon the end of which stud is screwed a nut member which retains the said breast plate 5 in normal operative position, and at 80 the same time maintains a spring 8 under tension between the lower end of the said breast plate and the upper portion of the said boss or hub 2. A further reason for the above noted construction is that the same 85 affords a shock absorber or take-up for vibration during the operation of the tool.

Arranged near the center of the tool is a fixed stud 9 which is rigidly attached to the housing member 1 by means of threads 10. 90 At the outer end of this stud is rotatably mounted a hammer actuating disk member 11 which carries upon one of its sides near the periphery thereof, a plurality of cam-like members or protuberances 12. It is obvious that any number of these cam-like members may be used and we have found in practice that for the ordinary operating rates of speed, six to nine of these members are sufficient, as will be disclosed in detail 95 later on. At the lower end of the said housing 1 is arranged another extending boss 13 which has a tapering cylindrical bore 14 therein, the bore being larger at its upper end than at its lower end 15. Immediately 100 below the said bore 14 is a threaded socket portion 16 which receives therein a lock-nut portion 17 which in turn serves to rigidly hold therein an arbor or chuck piece 18, which chuck piece holds the square shank 19 110

of the tool chuck 20. The tool chuck 20 is arranged after the fashion of the ordinary type to hold therein an operating tool 21; in the present case a stone cutting tool known 5 as a rock drill.

In the bore 13 is placed a cylindrical member 22 which is known as the hammer, and the said hammer is so arranged at its upper end that a portion of it is flattened 10 away as at 23, and below the flattened portion is arrayed a cam groove 24, the said cam groove being curved, the same developed from a radius or a point 25, as shown in Fig. 2. This groove in Fig. 1 is shown 15 as being deep enough to receive and permit the passage therethrough of the cam elements 12 which project from the side of the actuator member 11, and during the passage of the said members by the rotation of 20 the said disk in the direction of the arrow 250, Fig. 2, it is obvious that the oncoming portion of one of the cams 12 engages the wall of the groove in the hammer 22, and raises the hammer until the said cam has 25 passed through the said groove when the hammer 22 immediately drops. The dropping of the said hammer in the present case is accentuated by an energy-storing means in the form of a heart-shaped spring element 26, which is shown in Fig. 2 as being 30 comprised of a flat spring with an indented portion 27 in the middle thereof which is in engagement with a pin 28. The two ends of 35 said spring member 26 are then curved downwardly and brought together at a point 29, and are there received in a slot 30 which is cut into the upper end of the hammer member 22.

The pin member 28, which engages and 40 holds the spring in operative position against the hammer 22, is eccentrically secured upon a stud 31 which is rotatably mounted in the back wall of the housing 1. Suitably affixed to this stud 31 is a handle 45 32 which is held in operative connection to the said stud by any suitable means, in the present instance shown as a nut 33. Upon the housing 1, and immediately beneath the handle 32, in radial relation to the said 50 stud 31, is arranged a semi-circular rib 34 which has arranged on the surface thereof a plurality of depressions 35.

The handle 32 has arranged upon it a corresponding point or detent 36, and the said 55 handle being of thin flexible metal may be withdrawn so as to clear any of the said holes 35 and upon the rotation of the handle about the axis of the stud 31, the pin 28 is caused to shift up and down thereby increasing or decreasing the amount of tension on the spring 26, and when the desired point is 60 reached the detent 36 is entered into one of the holes 35, thereby locking the pin 28 against any further movement until desired.

It is natural in hammer construction of this type, where the hammer member 22 is arranged to reciprocate in a bore, that a great amount of side friction is developed in operating the said hammer, thereby increasing the work that the operator must overcome, especially when this device is operated by means of a hand crank, and to overcome this difficulty the previously mentioned bore 14 was enlarged at its upper 70 end and brought down to the normal diameter of the hammer 22 at the lower end. For the purpose of preventing this tapering bore from creating trouble during the operation and to also keep the said plunger 75 in nearly axial alignment with the said bore, we have arranged at the upper end of the said hammer a slot 37, in which is pivotally attached a link 38, the other end of which is pivotally attached to the casting, as at 39. 80 It is obvious that the up and down motion of the hammer 22 causes this link to move up and down therewith, the said link constraining the hammer to reciprocate to and fro under the action of the cam members 12, 85 and at the same time to prevent all side thrust against the wall of the bore caused by the said actuator. This link and its method of mounting also acts to prevent the 90 said hammer from rotating in its bore, thereby blocking the said cam members 12 and preventing the rotation of the disk. 95

It is evident that any means or source of power may be used to cause the rotation of the actuator disk 11, and while any type of 100 motor may be used therefor, we have disclosed in the present instance, a crank member 40, which is mounted upon the hub of the cam disk 11, the said crank having at its opposite end a handle 41 shown in Fig. 1. 105 A second handle 42 may be provided at a convenient point on the opposite side of the crank or operating side for the purpose of enabling the operator to guide the said tool during its operation. 110

We have further provided on the lower extending lug 13 a limiting stop 43 which may be made adjustable so as to be raised or lowered, thereby increasing or decreasing the amount of cutting where a rock drill is 115 used. This device, of course, may be dispensed with and a steadyng or foot fixture, not shown, be used in its place where the device is used for riveting or un-setting.

For the purpose of more fully disclosing 120 the device, reference may be had to Figs. 3 and 4 wherein is shown an arrow 44 which indicates the direction of rotation of the cam disk 11 which carries upon one of its faces the cam or lifting members 12. 125

In Fig. 3 is shown the cam face 120 just entering the hammer groove 24, and the hammer is thereby lifted from the shank 19 of the tool carrier, thereby compressing the resilient or spring member 26. 130

In Fig. 4 the hammer portion is shown as being near the limit of its upward stroke and the cam face 120 is about to leave the said cam groove 24, thereby permitting the hammer to impact sharply upon the upper portion of the tool carrier shank 19 and delivering a heavy blow. One of the important features of this cam action is that owing to the peculiar radial relation of the 5 said cam groove 24, previously referred to, and the radial position of the operating or lifting faces 121 of the cams 12, the two said operating faces remain in constant contact with one another throughout their entire 10 length, thereby distributing the wear over a greater surface and increasing the life of the device. This feature of the curving of the said face, is indicated by the radial line A which is set off a certain distance from, or 15 20 is tangential to, the center B of the said cam disk, and all of the said cam portions 12 are developed from the said relative dimensions, thereby presenting to the hammer groove 24 successively, during one rotation 25 of the disk, a pre-determined number of reciprocations and giving the operating tool a certain number of reciprocations per rotation.

Owing to the above noted construction 30 and the ease with which the device may be operated, it is possible to operate the cam disk member 11 at a much greater rate of speed than is usual in devices of this character, with the result that the hammer 22 35 instead of dropping in its proper cycle to be lifted by the next succeeding cam, will deliver its force on the next succeeding cam member instead of on the shank 19 of the tool holder 20. The force of this blow 40 would then be lost and damage might be done to the tool, such as for instance, the cams may be battered up or possibly in some cases broken off entirely, and to obviate this difficulty there is shown in Figs. 10 and 45 11 another type of cam disk 111, which is provided with a plurality of teeth 112; these teeth are shown in Fig. 12, which view is a fragmentary section taken on the line 12—12, Fig. 10. In all other respects the tool 50 shown in the above noted views is the same as that shown in Figs. 1, 2, 3, and 4.

For the purpose of preventing the hammer 22, Figs. 10 and 11, from striking the teeth 112 instead of being lifted by them, we 55 have changed the conformation of the cam disk and modified the hammer member 22 in such a manner that a slightly rounded shouldered projection 144, on the lower part of the hammer groove 24, is also utilized 60 as a cam in combination with said disk 111 so as to return the said hammer in case the same lags during the operation of the tool. The cam disk instead of being a circular member, as 11 in Figs. 1 and 2, is in the 65 present case cut back from the teeth in such

a manner as to leave the straight face 45 on the front edge of each oncoming cam, and as indicated at 46 in Fig. 11, the face 45 must force the hammer downwardly before the next oncoming cam engages in the said cam groove to lift. It will be seen, therefore, that the above noted construction will act as a limiting means to the possible number of rotations per minute of the said cam disk 111 by the operator. 70

Fig. 13 is a fragmentary sectional view of the hammer member 22 showing the modification of the hammer groove and the said cam 111, and their method of engagement during the operating portion of the 80 stroke, together with the front edge 46 of the said cam portion 112, showing the said face 46 in alignment with the hammer groove cam portion 45. By referring to Fig. 8, there will be seen a side elevation of the 85 hammer 22 which is used in the device disclosed in Figs. 1, 2, 3 and 4, and it will be noted that the face 47 of the said hammer does not terminate in the groove as in Fig. 13, but is cut back far enough from the groove 90 48 to give a clearance which is indicated at 48, Figs. 3 and 4.

Fig. 14 is a view taken on line 14—14 of Fig. 11, and shows the relative position of the cam disk 111 to the hammer 22. It may 95 also be noted that the last described cam disk 111 may either be a casting or may be made of sheet metal stamping of requisite thickness.

Having thus described our invention, we 100 claim:

1. The combination in a percussion hammer, of a housing, a grooved reciprocating plunger in said housing, a guide link for said plunger, a tension means for said plunger, and a rotatable disk having means for engaging the groove in said plunger to retract the hammer. 105

2. The combination of a housing, a hammer guided to reciprocate in the housing, an annular spring connected at diametrically opposite parts to the hammer and to the casing respectively to move the hammer in one direction, a rotatable actuator provided with a circular series of cams thereon, the hammer having a shoulder portion engaged by said cams successively as the actuator is rotated to thereby raise the hammer and compress the spring, whereby the hammer is advanced by the spring as released from the cams successively, the connection between the spring and the casing comprising a stud rotatable in the casing, a pin eccentrically mounted on the stud and engaging the spring, and means for securing the stud in 115 different positions to vary the tension of the spring. 120

3. The combination of a housing, a hammer guided to reciprocate in the housing, an annular spring connected at diametrically 130

opposite parts to the hammer and to the casing respectively to move the hammer in one direction, a rotatable actuator provided with a circular series of cams thereon, the hammer having a shoulder portion engaged by said cams successively as the actuator is rotated to thereby raise the hammer and compress the spring, whereby the hammer is advanced by the spring as released from the cams successively, a second shoulder on the hammer, and a second series of cams on the actuator arranged to engage said second shoulder in alternation with the engagement with the other cams with the first mentioned shoulder, to insure return of the hammer when raised by the said first cams.

4. The combination of a housing, a hammer guided to reciprocate in the housing, an annular spring connected at diametrically opposite parts to the hammer and to the casing respectively to move the hammer in one direction, a rotatable actuator provided with a circular series of cams thereon, the hammer having a shoulder portion engaged by said cams successively as the actuator is rotated to thereby raise the hammer and compress the spring, whereby the hammer is advanced by the spring as released from the cams successively, and a link pivoted to the hammer and extending transversely thereto with its other end pivoted on the casing and arranged to prevent the hammer from binding in its guideway in the casing.

5. In a percussion hammer, a housing having a tapered guideway, a hammer mounted to reciprocate in such guideway, a link pivoted to the rear end of the hammer and to the housing to cause the hammer to slide free of the guideway at the rear end of the guideway, a compression member arranged to advance the hammer when retracted, and a series of rotatable cams intersecting the hammer and arranged to retract the hammer.

45 6. The combination of a housing, a hammer guided to reciprocate in the housing, a spring connected to the hammer and to the casing to move the hammer in one direction,

a rotatable actuator provided with a circular series of cams thereon, the hammer having a shoulder portion engaged by said cams successively as the actuator is rotated to thereby raise the hammer and compress the spring, whereby the hammer is advanced by the spring as released from the cams successively, the connection between the spring and the casing comprising a stud rotatable in the casing, a pin eccentrically mounted on the stud and engaging the spring, and means for securing the stud in different positions to vary the tension of the spring.

7. A hammer comprising a substantially cylindrical housing provided with an axial mounting for a cam and two diametrically opposed limbs, one of said limbs comprising a hammer socket and the other comprising an abutment, a hammer operable in said socket, extending into said housing and there provided with a cam-engaging shoulder; revoluble on said mounting a cam disk and thereon a plurality of cams adapted to engage, retract and release said hammer; an adjustable spring strained between said hammer and housing; and operating means connected with said cam disk.

8. A hammer comprising a housing provided with a mounting for a cam and two diametrically opposed limbs, one of said limbs comprising a hammer socket and the other comprising an abutment, a hammer operable in said socket, extending into said housing and there provided with a convex cam-engaging face inclined to the hammer axis; revoluble on said mounting a cam disk and thereon a plurality of cams formed with faces concave and secant to said disk, and corresponding to and adapted to engage, retract and release said hammer; an adjustable spring strained between said hammer and housing; and operating means connected with said cam disk.
